Specification for Design.

Patented Nov. 3, 1914.

Application filed June 9, 1913. Serial No. 772,697. Term of patent 14 years.

To all whom it may concern:

Be it known that I, FRANK M. SCHAEFER, a citizen of the United States, and residing in the city of Chicago, county of Cook, and State of Illinois, have invented a new, original, and ornamental Design for Meat-Blocks or Similar Articles, of which the following is a specification, reference being had to the accompanying drawings, forming a part thereof.

In the drawings: Figure 1 is a side elevation of a meat block showing my design. Fig. 2 is a top plan view thereof.

I claim:

The ornamental design for a meat block or similar article, as shown.

In witness whereof I have hereunto subscribed my name in the presence of two subscribing witnesses.

FRANK M. SCHAEFER.
